UNITED STATES PATENT OFFICE.

JOHN D. LEMEX, OF TULSA, OKLAHOMA.

SUCKER-ROD HOOK.

Application filed June 24, 1927. Serial No. 201,149.

My invention relates to improvements in hooks, and more particularly to sucker rod hooks used in connection with sucker rod elevators employed for elevating or lowering oil well sucker or pumping rods.

The prime object of the present invention is to provide a sucker rod hook of simple and strong construction, embodying a locking or latch means for preventing the hook 10 from becoming accidentally disengaged from an elevator or other device to which it is applied.

Further objects of the present invention are, to provide new and improved locking 15 or latch mechanism and means for actuating the locking mechanism, said mechanism and actuating means being wholly contained within the hook structure; to provide a hook structure so designed that it has no projecting 20 parts to catch or hang on the derrick or rigging; and to provide a safe and convenient handle for the operator.

Various additional objects and advantages will either be pointed out or become apparent 25 from a consideration of an operative embodiment as hereinafter described and as illustrated by the accompanying drawings.

In the drawings, which illustrate an application of my invention:

30 Fig. 1 is a front elevational view of a hook embodying my invention;

Fig. 2, a side elevational view;

Fig. 3, a sectional view taken on line III—III of Fig. 2; and

35 Fig. 4, a view similar to Fig. 3, taken on line IV—IV of Fig. 2.

Referring to the drawings, and as preferred, the sucker rod hook designated generally by the numeral 5 includes an elongated body 6 provided with a neck 7 having a slightly reduced and threaded end portion 8. 9 designates a clevis member designed, when applied to the hook, to swivel on the neck 7 and is held in place thereon by a lock nut 11 45 carried on the threaded portion 8 of the neck.

The elongated body portion of the hook is formed with a hand opening 12, and is cored or otherwise constructed to provide 50 recesses, slots or spaces adapted to receive locking or latch means and actuating means for moving the locking means into and out of locking positions. As shown, the body is formed with a horizontally disposed space 55 or recess 13 having an inclined bottom wall

14, a front vertically extending inclined recess 15 designed to receive a latch or locking bar or member 16, and a vertically extending rear recess or space 17 having an enlargement 18 at its upper end. 60

Locking bar 16 is slidably mounted in the recess 15 and is disposed at a slight angle to the vertical axis of the body of the hook. Bar 16 is formed with an elongated slot 19 and with an apertured lug 20. Said bar 16 65 is guided and positioned in the recess 15 by means of a pin 21 cooperating with the slot 19 thereof.

The locking bar actuating mechanism is wholly contained within the hook structure 70 and, as illustrated and as preferred, includes a bell crank lever 22 fulcrumed on a pin 23 and having its long arm 24 at one end forked and secured to the apertured lug 20 of the bar 16 by a pin 25. The short arm 26 of the 75 bell crank lever is connected to an operating lever or handle 27 by means of a pin 28. The bell crank lever 22 and its operative connections are disposed in the cored-out portion or recess 13, and the said lever 27 80 extends upwardly through hand opening 12 and has a reduced upper end 29 designed to engage a stop wall or shoulder 30 to limit the inward movement of the said spring-pressed operating lever. 85

Arranged to bear against the hand lever 27, I provide a flat spring 31 having its upper end secured to the body by any suitable means, for instance, by screws 32 having threaded engagement with the body. 90

The nose of the hook is preferably formed with an inclined face 33 designed to cooperate with an inclined face 34 formed on the lower end of the locking bar 16. These inclined faces in conjunction with the inclined 95 positioned bar and its connections tend to prevent an accidental movement of the locking bar to open position.

It will be understood that the locking bar may be readily moved into unlocked position 100 by pressing upon or grasping the operating lever 27 and moving it slightly against the pressure of the spring 31, and that the locking bar will be automatically returned to locked position by a release of lever 27. 105

What I claim is:

1. In a sucker rod hook, the combination with an elongated body, of a vertically slideable locking bar member operable within the body and disposed in a plane inclined to the 110

vertical axis of the body, and means for moving the locking member into and out of locking position.

2. In a sucker rod hook, the combination 5 with an elongated body, of a vertically slid- able locking bar member operable within the body and disposed in a plane inclined to the vertical axis of the body, and means for sliding the locking member into and out of locking position, said locking member and its actuating means being positioned and operable wholly within the hook structure.

3. In a sucker rod hook, the combination 15 with an elongated body formed with a ver- tically extending locking bar receiving re- cess, of a vertically slidable locking bar mounted in the recess and having an elong- ated slot, a pin in the recess cooperating 20 with the said slot for positioning and guid- ing the locking bar, and means for moving the locking bar into and out of locking position including a bell crank lever having an a spring-pressed operating lever, said locking bar and its actuating means being positioned 25 and operable wholly within the hook struc- ture.

4. In a sucker rod hook, the combination

with an elongated body formed with a ver- tically extending locking bar receiving re- cess, of a vertically slidable locking bar 30 mounted in the recess and having an elong- ated slot, a pin in the recess cooperating 35 with the said slot for positioning and guid- ing the locking bar, and means for moving the locking bar into and out of locking position including a bell crank lever having an arm thereof connected with the locking bar, and an operating lever connected with an arm of the bell crank lever.

5. In a sucker rod hook, a slidable locking 40 bar, and means for positively sliding the bar into unlocked position and automatically moving it into locked position.

6. In a sucker rod hook, a slidable locking 45 bar, and means for positively sliding the bar into unlocked position and automatically moving it into locked position, said means including a bell crank lever positioned within the hook body and a spring-pressed oper- 50 ating lever connected with the bell crank lever.

In testimony whereof I affix my signature.

JOHN D. LEMEX.
